UNITED STATES PATENT OFFICE.

WILLIAM A. GALBRAITH, OF FLINT, MICHIGAN.

SULKY.

SPECIFICATION forming part of Letters Patent No. 508,415, dated November 14, 1893.

Application filed March 30, 1893. Serial No. 468,405. (No model.)

To all whom it may concern:

Be it known that I, WILLIAM A. GALBRAITH, a citizen of the United States, residing at Flint, in the county of Genesee, State of Michigan, have invented certain new and useful Improvements in Sulkies; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in sulkies, and consists in a certain construction and arrangement of parts, as hereinafter fully set forth, the essential features of which being pointed out particularly in the claims.

The object of the invention is to construct a light and strong sulky adaptable to the use of wheels having pneumatic tires, and in which the construction is such that the employment 25 of an axle for connecting the wheels is obviated, enabling the sulky to be hitched more closely to the horse, and in which provision is made for adjusting the vehicle for horses of various sizes, all of which is attained by the 30 mechanism illustrated in the accompanying drawings, in which—

Figure 1 is a rear elevation of my improved sulky. Fig. 2 is a side elevation of same. Fig. 3 is a plan view. Fig. 4 is a vertical section on dotted line 4—4 of Fig. 3. Fig. 5 is a vertical section on dotted line 5—5 of Fig. 3.

Referring to the letters of reference, A designates the thills, which are bent downward and rearward near their rear ends, forming 40 the parallel end portions A' that extend horizontally rearward, in a plane much lower than the forward ends thereof.

B and B' are parallel trussed bows or arches that constitute the frame which supports the 45 seats C, and which span between the rear end portions A' of the thills, upon which the ends of said trusses rest, and to which they are firmly secured, as shown at a. The rear truss B' is somewhat the higher of the two, 50 so as to give the proper pitch to the seat.

D designates the circle-bar, whose ends extend onto and are secured to the raised por-

tions of the thills, the rearwardly curved portion of said bar being supported by the diverging brace-rods b, which are attached to the rear truss B' and extend obliquely forward to said bar. Mounted on the circle bar, 55 is the whiffletree E, which is pivoted to said bar by means of the bolt c, the upper end of which is stayed by the short brace d, extending rearwardly from the truss B. Attached to the inner face of the circle bar and extending forward onto the thills, are the curved braces F, which are provided with a loop e that forms a stirrup or foot rest for the driver. 60

Extending laterally from the base of the trusses, on each side of the frame, are the bracket arms G. Depending from the outer ends of said brackets, are the converging brace-rods f, that are united at their lower 70 ends to an inclined plate h, having slots in its under edge, adapted to receive the outer end of the spindle i of the vehicle wheel as shown in Figs. 2 and 5.

f' indicates similar brace-rods that depend 75 from said brackets, approximately parallel to the braces f, and that are attached at their lower ends to an inclined plate h' having slots in its lower edge adapted to receive the inner end of the spindle i of the wheel. Said wheel 80 is mounted on the spindle between the braces f, f', the bearing cones o on said spindle being embraced by said plates h h', and the wheel is secured in the frame by clamping said plates between said cones and the nuts 85 d' on the ends of said spindle, as clearly shown in Fig. 3. This manner of securing the spindle in the slots in the inclined edges of the plates h, h', enables the seat supporting frame to be adjusted forward or backward to balance the weight of the driver, as desired, and the thills raised or lowered, according to the height of the horse, by simply loosening the nuts o' and moving the spindle forward or backward as required. 90

Extending from the under face of the rear ends of the thills, are the inclined braces m, which are attached to the inner plates h, and brace the wheel frame laterally.

Attached to the outer face of the thills, and curving rearwardly around the wheels, to the curved bar H that connects the rear ends of the thills, are the guard braces I, that serve to brace the thills and the wheel frame, and 100

form a guard which prevents the locking of the wheels with another vehicle.

Having thus fully set forth my invention, what I claim as new, and desire to secure by 5 Letters Patent, is—

1. In a sulky, the combination of the thills, the arched trusses connecting said thills, the wheel frames depending from said trusses, and the wheels adjustably mounted therein.
- 10 2. In a sulky, the combination with the sulky frame, of the wheel frame, having opposed plates provided with a series of registering slots, the wheel, the spindle of said wheel adapted to be received in the slots of said plates.
- 15 3. In a sulky, the combination with the sulky frame, of the wheel frame provided with parallel inclined plates having corresponding slots in their under edges, the wheel, the spindle of said wheel adapted to be removably secured in the slots of said plates.
- 20 4. In a sulky, the combination of the thills, the trussed arches connecting said thills, the brackets extending horizontally from said trusses, the converging brace-rods depending

from said brackets, and the wheels journaled at the lower ends of said rods.

5. In a sulky, the combination of the thills, the arch connecting said thills, the wheel frames attached to said arch, the curved 3c guard and brace attached to the thills, and passing around the wheel frame.

6. In a sulky, the combination of the thills, the arched frame connecting said thills, the wheel - frames depending from the arched 35 frame, and the wheels adjustably mounted in said wheel-frames.

7. In a sulky, the combination of the thills, the arch connecting said thills, the brackets extending horizontally from said arch, the 40 converging brace-rods depending from said brackets, and the wheels journaled at the lower ends of said rods.

In testimony whereof I affix my signature in presence of two witnesses.

WILLIAM A. GALBRAITH.
